CLAIM

The ornamental design for a core for a pillow, as shown and described.

DESCRIPTION

1. Core for a pillow

1.1 is a front view of a core for a pillow of the present invention;

1.2 is a back view thereof;

1.3 is a top plan view thereof;

1.4 is a bottom view thereof;

1.5 is a right side view thereof;

1.6 is a left side view thereof;

1.7 is a perspective view thereof;

1.8 is a cross-sectional view taken along line 8-8 in figure 1.3;

1.9 is a cross-sectional view taken along line 9-9 in figure 1.3;

1.10 is an enlarged detail view of area 10 circumscribed within figure 1.3;

1.11 is an enlarged detail view of area 11 circumscribed within figure 1.7;

1.12 is an enlarged detail view of area 12 circumscribed within figure 1.8;

1.13 is an enlarged detail view of area 13 circumscribed within figure 1.9.

The core for a pillow is intended to be used by attaching it to a pillow cover. The dot dash dot broken lines denote the boundaries of the claim and form no part thereof. The evenly spaced broken lines depict portions of the core for a pillow that form no part of the claimed design. Broken lines which indicate the boundaries of the detail areas form no part of the claimed design.
